UNITED STATES PATENT OFFICE.

JOHN KERNAGHAN, OF SAN FRANCISCO, CALIFORNIA.

PROTECTIVE FRAME-WORK FOR LEVEES, DAMS, &c.

SPECIFICATION forming part of Letters Patent No. 352,544, dated November 16, 1886.

Application filed April 20, 1885. Serial No. 162,852. (No model.)

To all whom it may concern:

Be it known that I, JOHN KERNAGHAN, a resident of San Francisco, State of California, have invented a new and useful Protective 5 Frame-Work for Levees, Dams, and Embankments; and I hereby declare that the following is a full, clear, and exact description of the same, reference being had to the accompanying drawings.

10 My invention relates to an improved means for constructing and protecting levees, dams, and embankments by the use of a frame-work of timber.

15 The following description fully explains the nature of my said invention and the manner in which I proceed to construct, apply, and use the same, the accompanying drawings being referred to by figures and letters.

Figure 1 represents the frame-work with 20 double bents. Fig. 2 gives a view of the same with single bents. Fig. 3 represents a section of an old levee repaired with the frame-work with single bents. Fig. 4 represents a section of a single bent. Fig. 5 represents a section of a double bent.

25 Referring to Fig. 1, the double bent *a*, triangular in form and braced by the diagonal brace *a'* of the frame-work with longitudinal stringers *b* attached, and vertical planks forming apron *c*.

Referring to Fig. 2, the single bent *d* of the frame-work with longitudinal stringers *b* attached, and vertical planks forming apron *c*.

30 Referring to Fig. 3, a section of an old levee is cut, *e*, and repaired and fortified by the frame-work with single bents *d*.

Referring to Fig. 4, a section of the single bent *d*, triangular in form and having the bracing-bars *a'*.

40 Referring to Fig. 5, a section of the double bent *a*, triangular in form and having the bearing-bars *a'*.

In constructing a levee, or dam, or an embankment the employment of my frame-work 45 will not only greatly increase the resisting-power of the work, but will add to its protection. The frame-work, consisting of single or double bents and longitudinal stringers,

Figs. 1 and 2, may be constructed of rough timber, spotted and faced at the points of junction, and fastened with iron bolts. If it is necessary to protect an embankment from the wearing action of the water, its exposed side is covered by an apron formed of planks placed vertically, and fastened with tree-nails 50 and iron bolts. The frame-work may be of any dimensions required to suit the plans of the engineer, and the bents may be placed at short or greater distances apart.

In embanking for a railway over a low 60 area, the use of my frame-work constructed with double bents *a*, Fig. 5, and filled in with earth and stone, will give a solid and durable road, the sides of which will neither slide off nor wear away. In cutting a track for a 65 railway around a side hill, the material of which is loose, the frame-work with single bents *d*, Fig. 4, filled in, and the inclined outer side covered with an apron made of rough 70 planks, will protect the work from moving and sliding, and tend to make a solid and permanent road.

The bents are provided at the upper and lower corners of their oblique or inclined sides with edge recesses, *g*, for the reception 75 of the longitudinal stringers *C*, and also at intermediate points on the same sides with similar recesses, as shown. These recesses may in some cases be of dovetail or other suitable form, so as to securely hold the stringers 80 without the use of nails or other fastening devices. When the recesses are of dovetail form, the engaging portion of the stringers should be of a conformable contour. The bents are preferably of truncated triangular 85 form; but in some cases such a shaped bent may be divided by a central vertical line, and used in a similar manner. The former construction is preferable, however, when it is desirable to make a roadway out of the embankment.

I am aware that it is not new to construct 90 dams and levees of bents connected by longitudinal rails, and fill the same in with stones, earth, and the like, and therefore do not claim 95 such devices broadly.

Having thus fully described my invention, what I claim, and desire to secure by Letters Patent, is—

The combination, with a series of triangular bents having diagonally arranged bracing bars and notches, of a series of longitudinal stringers seated in said notches and secured to the bents, and a series of vertical slats or planks secured to the stringers, as set forth.

In testimony whereof I have hereunto set my hand and seal.

JOHN KERNAGHAN. [L. S.]
